[57] **CLAIM**

The ornamental design for a captive nut, as shown and described.

DESCRIPTION

FIG. 1 is a top plan view of a captive nut showing my new design;

FIG. 2 is a front elevation view thereof, the remaining sides being identical;

FIG. 3 is a bottom plan view thereof;

FIG. 4 is a top plan view of an alternate embodiment of FIG. 1;

FIG. 5 is a bottom plan view of FIG. 4;

FIG. 6 is a front elevation view of an alternate embodiment of FIG. 1, the remaining sides being identical; and,

FIG. 7 is a front elevation view of an alternate embodiment of FIG. 1, the remaining sides being identical.

The alternate embodiments shown in FIGS. 6 and 7 may have a top as shown in FIGS. 1 and 4.
